BOTTLE

Frank L. Twitty, Bronxville, N. Y.

Application December 15, 1949, Serial No. 6,642

Term of patent 14 years

(Cl. D58—6)

To all whom it may concern:

Be it known that I, Frank L. Twitty, a citizen of the United States, residing at Bronxville, in the county of Westchester and State of New York, have invented a new, original, and ornamental Design for a Bottle, of which the following is a specification, reference being had to the accompanying drawing, forming part thereof.

Fig. 1 is a front elevation of a bottle embodying my new design;

Fig. 2 is an end view of the same; and
Fig. 3 is a top plan view thereof.

I claim:

The ornamental design for a bottle, substantially as shown.

FRANK L. TWITTY.
